G. M. HARNISCH, OF CHICAGO, ILLINOIS.

Letters Patent No. 92,188, dated July 6, 1869.

IMPROVEMENT IN HARNESS.

The Schedule referred to in these Letters Patent and making part of the same.

To all whom this may concern:

Be it known that I, G. M. HARNISCH, of Chicago, in the county of Cook, and State of Illinois, have invented an Improvement in Harness; and I do hereby declare that the following is a full, clear, and exact description thereof, which will enable those skilled in the art to make and use the same, reference being had to the accompanying drawings, and letters marked thereon, making a part of this specification, in which—

Figure 1 is an elevation of that part of the harness which I have improved.

Figure 2, an elevation of the same, with the long tug removed.

Figure 3, a section taken through fig. 1, on the line Z Z.

The nature of the present invention consists in the novel means employed to connect the back-strap and belly-band, in combination with adjustable tugs, which are arranged to hold the connecting-straps in place when they are adjusted.

A represents the sweat-leather, and B, the hames-tug of an ordinary horse-harness.

This tug has two or more nuts D fastened to it, by means of rivets F, fig. 3, in order that one or more thumb-screws E may be put through a long tug, C, and hold it firmly to the hames-tug B.

A looped attachment or buckle, M L J N G K P, is used to connect the tug to the strap fastening on to the belly-band and back-strap.

The part N is a bar, around which the hames-tug B is looped, and G H are the bars under which the long tug C passes.

The centre part K, fig. 3, connects with the bars P, and supports a short lug or pin, J, which passes through the connecting-strap I I'.

This strap passes through loops L, and also through suitable openings m m, made in the sweat-leather A, figs. 1 and 2, and it is held on the pin J by means of the long tug C, which fits closely against the end of the pin, and also bears on the strap.

It will be seen from this description, that the strap I I', passing through the sweat-leather, is drawn, when buckled to the other parts of the harness, closely down on to the bar K, figs. 2 and 3, and consequently cannot be displaced by accident from the pin J, when the tug C is in position, as shown at fig. 1.

The tug B is to be attached to the hames by means of any ordinary hook fastened to its end x.

The upper end I' of the strap I I' is to be buckled to the back-strap, and the lower end I to the belly-band of the ordinary harness.

The adjustment to bring the tug C straight with the line of draught, is made by placing the pin J in one of the holes P, above or below, as the case may require.

The tug C is adjusted by removing the screws E, bringing the tug forward or back one hole, and then turning in one or both screws, according to the position of the nuts; one screw, however, being sufficient to hold the tug in place.

Having thus described my invention,

What I claim, and desire to secure by Letters Patent of the United States, is—

The combination of the strap I I', sweat-leather A, hames-tug B, tug C, nut E, buckle M N L J G K P, arranged as described, and for the purpose set forth.

G. M. HARNISCH.
